UNITED STATES PATENT OFFICE.

JOSEPH T. PAYNE, OF SWEET SPRINGS, MISSOURI.

SAFETY-PIN.

SPECIFICATION forming part of Letters Patent No. 601,981, dated April 5, 1898.

Application filed May 28, 1897. Serial No. 638,574. (No model.)

To all whom it may concern:

Be it known that I, JOSEPH T. PAYNE, a citizen of the United States, residing at Sweet Springs, in the county of Saline and State of Missouri, have invented certain new and useful Improvements in Safety-Pins; and I do declare the following to be a full, clear, and exact description of the invention, such as will enable others skilled in the art to which it appertains to make and use the same.

My invention relates to improvements in safety-pins; and the object is to provide a simple, cheap, and effective device of this class; and to this end the novelty consists in the construction, combination, and arrangement of the same, as will be hereinafter more fully described, and particularly pointed out in the claim.

In the accompanying drawings the same reference characters indicate the same parts of the invention.

Figure 1 is a perspective view of my improved safety-pin. Fig. 2 is a longitudinal section of the same. Fig. 3 is a detail perspective of the toothed end.

1 represents the body of the pin; 2, the integral spring-coil, and 3 the spring-tongue, which terminates in a pointed end 4, provided with a longitudinal eye 5. The free end of the body 1 is formed with a semicircular loop 6, and its immediate end is turned inwardly to form the tooth 7, which projects into the eye 5 of the tongue and is locked in place by a notch 8.

9 represents the sheet-metal guard which encompasses the loop 6, so as to project on each side of the tooth 7 and the pointed end of the tongue. This guard is fixed to the pin

by crimping the metal of which the shield is formed on each side, so as to encompass the loop to fix it in place and at the same time stiffen the pin.

When a pin of this construction is secured in place in a garment, it is practically impossible for it to become accidentally detached.

While I have described my improved pin-lock as applied to a safety-pin, it is evident that the same construction applies equally well to breastpins, brooches, belt-pins, and the like, and in fact it may be utilized wherever a clasp-pin lock of this nature is desirable.

Having thus fully described my invention, what I claim as new and useful, and desire to secure by Letters Patent of the United States, is—

The herein-described safety-pin comprising the body portion 1 formed with the loop 6 one of the terminal ends of which is turned upward to form a tooth 7 which is provided with a locking-notch 8 and the other end pointed and provided with an eye 5 adapted to engage said tooth and notch, and the sheet-metal guard secured to the said loop so as to protect the tooth and open on both sides, whereby the pointed end may engage said tooth from either side of the guard, substantially as shown and described.

In testimony whereof I hereto affix my signature in presence of two witnesses.

JOSEPH T. PAYNE.
